PORTABLE FAN

Raoul A. Lambert, Springfield, Mass., assignor to Westinghouse Electric Corporation, a corporation of Pennsylvania

Application August 8, 1957, Serial No. 47,274

Term of patent 14 years

(Cl. D26—7)

FIG. 1.

FIG. 2.

FIG. 3.

FIG. 4.

FIG. 5.

Fig. 1 is a front perspective view of a portable fan embodying my new design;

Fig. 2 is a fragmentary rear perspective view of a portion of the fan of Fig. 1, showing a trunnion arm in detail;

Fig. 3 is a top plan view;

Fig. 4 is a rear elevational view; and

Fig. 5 is a side elevational view thereof.

The dominant features of the design, shown in solid lines, reside in the trunnion arms combined with their location at the bend in the stand legs, which legs are spaced apart a distance less than the overall width of the fan housing.

I claim:

The ornamental design for a portable fan, substantially as shown and described.
